United States Patent Office

Des. 219,952
Patented Feb. 23, 1971

219,952

CLOSURE TOOL

George Yates, Jr., Glendale, Calif., assignor to Growth International Industries Corp., Cleveland, Ohio, a corporation of Delaware

Filed Oct. 13, 1969, Ser. No. 19,522

Term of patent 14 years

Int. Cl. D8—02

U.S. Cl. D8—40

FIG. 1 is a perspective view of a closure tool showing my new design;

FIG. 2 is a front elevational view thereof;

FIG. 3 is a right side elevational view thereof;

FIG. 4 is a top plan view thereof; and

FIG. 5 is a bottom plan view thereof.

The left side elevational view is substantially a mirror image of the right side elevational view.

I claim:

The ornamental design for a closure tool, as shown.
